J. L. CARBERY.
STEAM COOKING APPARATUS.
APPLICATION FILED MAR. 22, 1913.

1,108,967.

Patented Sept. 1, 1914.

UNITED STATES PATENT OFFICE.

JAMES L. CARBERY, OF ROCKHILL, SOUTH CAROLINA.

STEAM COOKING APPARATUS.

1,108,967.

Specification of Letters Patent.

Patented Sept. 1, 1914.

Application filed March 22, 1913. Serial No. 756,241.

To all whom it may concern:

Be it known that I, JAMES L. CARBERY, a citizen of the United States, residing at Rockhill, in the county of York and State of South Carolina, have invented certain new and useful Improvements in Steam Cooking Apparatus, of which the following is a specification.

My invention relates to steam cookers for sterilizing or processing fruits, vegetables or other food stuffs and has particular reference to such cookers of the closed or sealed type, wherein, different desired degrees of steam pressure may be obtained, for providing corresponding degrees of heat, and the elements of danger, such as explosions or other similar accidents are reduced to the minimum.

An important object of this invention is to provide means of the above mentioned character, which will reduce the time required for preserving fruits, vegetables and the like and increase the immunity of the same from subsequent deterioration or spoiling, due to action of unskilled bacteria, fungi, or spores of the same.

A further object of this invention is to provide a steam cooker of the above mentioned character, which is so constructed that the bottles, cans, or other receptacles, containing the material to be preserved, may be quickly and easily moved into and out of the same.

A further object of this invention is to provide a steam cooker of the above mentioned character, which is simple in construction, cheap to manufacture, and reliable in operation.

Other objects and advantages of this invention will be apparent during the course of the following description.

In the accompanying drawings, forming a part of this specification, and in which like numerals are employed to designate like parts throughout the same, Figure 1 is a central vertical longitudinal sectional view through the entire apparatus, parts thereof being shown in elevation, and Fig. 2 is an end view of the same.

In the drawings, wherein for the sake of illustration is shown a preferred embodiment of my invention, the numeral 6 designates a main shell or casing, forming the body portion of the apparatus. The lower end of the main shell 6 is closed by a bottom 7, as shown. The upper portion 8 of the

main shell 6 constitutes a processing or cooking chamber. The rear end of the main shell 6 is provided with an opening 9, the walls 10 of which are preferably slightly beveled or bent inwardly, for engaging with a door 11, the free edges of which are beveled or bent outwardly, as shown. This door is connected with the main shell 6 to swing in a horizontal plane, by means of hinges 12. Connected with the door 11 is a swinging latch 13, to engage a fixed catch 14 carried by the main shell 6, as shown. The swinging latch 13 engages the vertically inclined face 15 of the fixed catch 14, whereby upon the downward movement of the latch 13 within the fixed catch 14, the swinging latch will force the door 11 inwardly into firm engagement with the walls of the opening 9, for forming therewith a substantially steam tight joint. The door 11 is preferably provided upon its engaging inner surface with a sheet of packing 16.

Disposed within the main shell 6 are spaced horizontal guide rods or rails 17, which are rigidly connected with the sides of the main shell. These guide rods or rails are preferably L-shaped in cross-section and are spaced from the bottom 7 of the chamber 8, to be adjacent the lower end of the opening 9. Adapted to travel or slide longitudinally upon the rails 17 is a carriage, car or drawer 18, the sides of which are preferably formed open, as shown. This carriage, car or drawer is mounted upon wheels or roller bearings 19, engaging the rails or guide rods 17. At one end the carriage, car or drawer 18 is provided with a handle 20, which is used when the same is being moved through the opening 9. The bottles, cans or other receptacles containing the goods to be preserved, are preferably first placed in baskets, (not shown), which are placed within the carriage, car or drawer 18. Disposed above the carriage, car or drawer 18 are fixed horizontal rails or guide rods 17^a, engaged by a transverse strip or bar 18^a, attached to one end of the carriage 18. The function of this construction is to prevent the tilting of the carriage, car or drawer when partly withdrawn from the main shell 6.

Pivotedly connected with the bottom of the carriage, car or drawer 18 is a supporting leg 19^a, which is vertically disposed when the carriage is in its outer position and horizontally arranged when the carriage is moved into the main shell, as

shown. Any suitable means may be employed to support the free end of the leg 19^a, when the same is horizontally arranged.

- The lower portion of the main shell 6 beneath the rails 17 constitutes a water holding chamber 21. The water is supplied to the chamber 21 from a tank 22, which is disposed exteriorly of the main shell 6 and suitably connected therewith, as shown.
- 10 Connected with the lower end of the tank 22 is an outlet pipe 23, extending into the chamber 21. Within this chamber the outlet pipe 23 is provided with a valve 24, operated by a pivoted lever 25, which is moved 15 by a float 26. When the level of the water within the chamber 21 falls below a certain point, the float 26 is lowered whereby the valve 24 is opened to supply the water to the chamber until the desired level is regained.
- 20 At its upper end, the tank 22 is provided with an inlet pipe 27, carrying a removable cap 28. A pipe 29 serves to establish communication between the upper portion of the main shell 6 or the cooking chamber and 25 the upper end of the tank 22, whereby the pressure above and below the water within the tank 22, is balanced.

- The numeral 30 designates a furnace shell or casing, for receiving the lower end of the 30 main shell 6, these parts being detachably connected, as shown. It is thus seen that the main shell 6, may be removed from the furnace shell 30 and mounted upon a stove or the like. One end of the furnace shell is 35 provided with a fuel opening 31, which is normally closed by a preferably horizontally swinging door 32. This door is held in its closed position by latch means 33 and is also preferably provided with a damper 34. At 40 its opposite end the furnace shell 30 is provided with an outlet opening 35, discharging into an upstanding stack 36. This stack is connected with the tank 22 by horizontal and vertical strap irons 37 and 38, as shown.
- 45 The stack is provided with a damper 36^a.

- The bottom 7 is provided near and spaced from its opposite ends with upstanding tubes 39, covered by fusible caps 40. These caps are to be formed of a suitable metal 50 that will fuse when the heat within the shell 6 exceeds a certain degree, due to the very low level of the water within the chamber 21. It is thus seen that should the valve 24 and float means for operating the same, for 55 any reason, become inoperative, so that the water level within the chamber 21 should drop below the danger point, the caps 40 will fuse, whereby the steam pressure will be released and the remaining water and 60 steam discharged into the furnace shell 30 for extinguishing the fire. The function in providing two of the fusible caps 40 disposed near and spaced from the opposite

end of the main shell 6, is to provide means which will operate satisfactorily when the 65 main shell 6 is horizontally disposed or inclined.

I provide a safety valve structure 42 for regulating the pressure of steam maintained 70 within the shell 6.

The operation of the apparatus is as follows: The material to be preserved is put up in jars, cans or other receptacles, which are placed in baskets, which in turn are placed within the carriage 18. A suitable fire is 75 built within the furnace shell 30, which boils the water in the chamber 21, for generating the steam, which in turn cooks the material to be preserved. The valve structure 42 is normally closed and is adapted to quickly 80 reduce the pressure within the apparatus, when opened. To maintain constant the water level in chamber 21, I provide the float operated valve which automatically operates for withdrawing the water as needed from 85 the tank 22, and supplying the same to the chamber 21.

It is to be understood that the form of my invention, herewith shown and described is to be taken as a preferred example of the 90 same, and that certain changes in the shape, size and arrangement of parts may be resorted to without departing from the spirit of the invention or the scope of the subjoined claims.

Having described my invention, I claim:

1. In apparatus of the character described, a main closed shell having its upper portion constituting a processing chamber and its lower portion a water receiving chamber, 100 horizontal rails mounted within the processing chamber, a wheeled carriage mounted to travel upon the rails, means mounted within the main closed shell for preventing the carriage from tilting when moved to its 105 outer position, and means to heat the processing chamber.

2. In apparatus of the character described, a main closed shell having its upper portion constituting a processing chamber and its 110 lower portion a water receiving chamber, substantially horizontal rails mounted within the processing chamber, a carriage mounted to travel longitudinally upon the rails, guide rails disposed near the carriage, an 115 element attached to the carriage and operating beneath and in slidable engagement with the guide rails, and means to heat the water receiving chamber.

In testimony whereof I affix my signature 120 in presence of two witnesses.

JAS. L. CARBERY.
